UNITED STATES PATENT OFFICE

HAROLD DOUGLAS MACKIE, OF MANCHESTER, ENGLAND

DESIGN FOR A MASCOT FOR USE ON A MOTOR VEHICLE

Application filed October 27, 1931, Serial No. 41,542, and in Great Britain September 22, 1931. Term of patent 3½ years.

To all whom it may concern:

Be it known that I, HAROLD DOUGLAS MACKIE, a subject of the King of Great Britain, residing at Manchester, in the county of Lancaster, England, have invented a new, original, and ornamental Design for a Mascot for Use on a Motor Vehicle, of which the following is a specification, reference being had to the accompanying drawings, forming part thereof.

I claim:

The ornamental design for a mascot for use on a motor vehicle as shown.

HAROLD DOUGLAS MACKIE.
